(57) **CLAIM**

The ornamental design for an apparatus for preparing beverages, as shown and described.

DESCRIPTION

FIG. 1 is an isometric view of an apparatus for preparing beverages, showing our new design;

FIG. 2. is a front view thereof;

FIG. 3 is a rear view thereof;

FIG. 4 is a left view thereof;

FIG. 5 is a right view thereof; and,

FIG. 6 is a top view thereof.

The broken lines in the drawings depict portions of the apparatus for preparing beverages that form no part of the claimed design.
